WARM AIR FURNACE RADIATOR

Filed Dec. 15, 1926

UNITED STATES PATENT OFFICE.

HEINRICH JAEGLER, OF SALEM, OREGON.

WARM-AIR-FURNACE RADIATOR.

Application filed December 15, 1926. Serial No. 154,908.

My invention relates to warm air furnace radiators in which a casing with a baffle plate is interposed between the fire box and the smoke pipe.

5 The objects of my invention are to provide a radiator which is simple in construction and furnishes an extremely large surface for the heating of the circulating air.

10 Other objects and advantages are to be found in the construction and arrangement of parts as will be described in the specification and particularly pointed out in the appended claims.

15 I attain these objects with the mechanism illustrated in the accompanying drawing, in which:

Fig. 1 is a vertical longitudinal cross section through a warm air furnace showing the radiator in place.

20 Fig. 2 is a plan view of the radiator alone, partly in section.

Similar numerals refer to similar parts throughout the several views.

The radiator consists of a casing 1 circular in plan view and approximately elliptical in vertical cross section. On top of the casing 1 and at the center of the circle,

25 is a sleeve 2 integral with the casing 1, which extends upward into the corresponding sleeve 3 of the smoke pipe 4. This sleeve 2 serves as outlet. A similar sleeve 5 at the bottom of the casing 1 serves as inlet into the interior of the casing 1 and fits over a corresponding sleeve 6 at the top of

30 the fire box 7. The interior of the casing 1 is divided into an upper and lower chamber 8 and 9 respectively by a horizontal baffle plate 10 which is essentially smaller than the inner diameter of the casing 1 but integrally connected with said casing by a plurality of radially extending spokes or arms

35 11. The space between said arms 11 establishes communication between said upper and lower chambers 8 and 9. At the outer circumference of the casing 1 are disposed a plurality of radially extending fins 12. These fins extend close to the outer shell 13 of the furnace and are high enough to reach part way over the upper and lower surface

40 of the casing 1. A clean-out opening 14 at one side of the casing 1 extends outside the shell 13 of the furnace and is usually closed by a clean-out door 15.

45 As the fuel is consumed on the grate 16, the gases of combustion from the fire box

7 enter the lower chamber of the casing whence they are deflected by the baffle plate 10 toward the periphery of the latter to enter the upper chamber 8 in the casing 1 by means of the openings between the arms 11. 60 From the upper chamber 8 the gases are permitted to escape into the smoke pipe 4.

The circulating air ascends between the shell 13 of the furnace and the wall of the fire box 7 but then encounters a baffle plate 17 with a hole 18 at the center. This forces the air toward the inlet sleeve 5 and brings it into close contact with the lower surface of the casing 1. Further progress of the air must take place between the fins 12 before entrance into the register pipes 19 is permitted. The upper surface of the casing 1 radiates its heat generally into the space between the casing 1 and the top 20 of the furnace. 70

75 These are the essential elements of my invention. It now remains to enumerate incidental parts of construction shown in the drawing. The numeral 21 indicates the clean-out door for the smoke pipe 4, and the numerals 22 and 23 stand for the fire door and ash pit door respectively.

Having thus described my invention, it will be seen that my objects have been accomplished, and, though I have shown the preferred form of construction, I reserve to myself the right to make minor changes providing I do not violate the spirit and principle of my invention. 85

I claim:

1. In combination a warm air furnace having a fire box and a smoke pipe, with a radiator, circular in plan view and elliptical in cross section, said radiator comprising a casing communicating at the bottom with the fire box and at the top with the smoke pipe, said casing having a horizontal baffle plate dividing the interior of the casing into an upper and lower chamber, openings traversing said baffle plate at the periphery and establishing communication between the upper and lower chamber, and a plurality of vertical fins radiating from the outer circumference toward the shell of the furnace. 90

2. A radiator comprising a casing rectangular in plan view and elliptical in vertical cross section, a central inlet, a central outlet at the top of the casing, a horizontal baffle plate dividing the interior of the cas- 100

105

110

ing into an upper and lower chamber, the edge of the baffle plate being equidistant from the inner periphery of the casing, a plurality of arms connecting the edge of the baffle plate integrally with the inner periphery of the casing, and a plurality of vertical fins radiating from the outer pe-

riphery of the casing, said fins extending part way over the upper and lower surfaces of said casing.

Signed by me this 10th day of December, 1926.

HEINRICH JAEGLER.
